(57) **CLAIM**

D27/174, 175, 176, 177, 178, 179, 180,

The ornamental design for an electronic cigarette, as shown
and described.

D27/181, 182, 183, 184, 185, 186, 187,

DESCRIPTION

D27/188, 189, 190, 191, 192, 193,

FIG. 1 is a front elevation view of an electronic cigarette;

D28/91.1; D23/360, 362; D24/110,

FIG. 2 is a rear elevation view thereof;

D24/110.4, 110.5, 110.6, 113

FIG. 3 is a left-side elevation view thereof;

CPC A24F 40/10; A24F 40/40; A24F 40/46;

FIG. 4 is a right-side elevation view thereof;

A24F 40/42; A24F 40/44; A24F 40/485;

FIG. 5 is a top plan view thereof;

A24F 40/50; A24F 40/60; A24F 40/90;

FIG. 6 is a bottom plan view thereof; and,

A24F 40/53; A24F 40/70; A24F 40/48;

FIG. 7 is a perspective view thereof.

A24F 40/51; A24F 40/57; A24F 40/05;

(Continued)

A24F 40/65; A24F 40/20; A24F 47/002;

A24F 40/30; A24F 7/00; A24F 47/00;

A24F 1/32; A24F 40/00; A24F 40/49;

A24F 40/85; A24F 40/95; A24F 7/04;

A24F 9/16; A24F 47/008; A24F 15/015;

A24F 40/465; A24F 42/60; A24F 1/02;

A24F 2700/03; A24F 47/006; A24F

13/00; A24F 13/14; A24F 15/01; A24F

15/12; A24F 15/14; A24F 15/18; A24F

42/00; A24F 42/10; A24F 7/02; A24F

47/004; A24F 1/00; A24F 42/20; A61M

The broken lines in the drawings depict portions of the electronic cigarette that form no part of the claimed design.

2205/3317; A61M 2205/50; A61M

2205/52; A61M 2205/3368; A24B 15/167
